UNITED STATES PATENT OFFICE.

JAMES HAROLD LANE, OF BOSTON, MASSACHUSETTS, ASSIGNOR TO UNITED DRUG COMPANY, OF BOSTON, MASSACHUSETTS, A CORPORATION OF MASSACHUSETTS.

DESIGN FOR A MEDICINAL TABLET OR SIMILAR ARTICLE.

60,248.

Specification for Design.

Patented Jan. 17, 1922.

Application filed January 15, 1921. Serial No. 437,602. Term of patent 14 years.

To all whom it may concern:

Be it known that I, JAMES HAROLD LANE, a citizen of the United States, residing at Boston, in the county of Suffolk and Commonwealth of Massachusetts, have invented a new, original, and ornamental Design for a Medicinal Tablet or Similar Article, of which the following is a specification, reference being had to the accompanying drawing, forming part hereof.

Fig. 1 is a plan view of a medicinal tablet, showing my new design, and Fig. 2 is a perspective view of the same.

I claim:

The ornamental design for a medicinal tablet, or similar article, as shown.

Dated January 11, 1921.

JAMES HAROLD LANE.

Witnesses:

RAY HENRY,

JAMES FREDERICK MORRISON.
